UNITED STATES PATENT OFFICE

101,709

DESIGN FOR A TEXTILE DRAPERY PIECE OR SIMILAR ARTICLE

Everett Nutter, Sanford, Maine, assignor to Goodall Worsted Company, Sanford, Maine, a corporation of Maine

Application June 25, 1936, Serial No. 63,476

Term of patent 3½ years

To all whom it may concern:

Be it known that I, Everett Nutter, a citizen of the United States of America, residing at Sanford, county of York, and State of Maine, have invented a new, original, and ornamental Design for a Textile Drapery Piece or Similar Article, of which the following is a specification, reference being had to the accompanying drawing, forming part thereof, wherein—

The figure is a plan view of a textile drapery piece or similar article, showing my new design.
I claim:

The ornamental design for a textile drapery piece or similar article, substantially as shown.

EVERETT NUTTER.
